UNITED STATES PATENT OFFICE.

RUSSELL E. NELLES, OF READING, PENNSYLVANIA, ASSIGNOR TO READING CHAIN & BLOCK CORPORATION, OF READING, PENNSYLVANIA, A CORPORATION OF PENNSYLVANIA.

ADJUSTABLE END TRUCK.

Application filed January 28, 1927. Serial No. 164,269.

This invention relates to improvements in adjustable end trucks for overhead carriers or travelling cranes, and the object in the present instance is to provide a cheap and simple means for securing adjustment of the end trucks on the beams, to the end that a certain standardization of the parts may be accomplished and provision made for such adjustment in the workshop before the parts are shipped for assembly at the point where the carrier is to be used.

To this end I have provided a plate capable of sliding longitudinally on the beam, and provided with a set of clamps and bolts, whereby the plates may be set at any desired distance from each other when the structure is erected.

The invention is more fully described in the following specification and clearly illustrated in the accompanying drawing, in which:

Figure 1 is an elevational view, showing the beam broken away, and disclosing both end trucks mounted thereon.

Figure 2 is a plan view of one of the adjustable plates.

Figure 3 is an end view of the parts shown in Figure 2.

The numeral 1 designates the beam to which the truck ends are to be adjustably attached. The numeral 2 designates the trucks and each is mounted on a plate 4. These plates are provided with perforations to accommodate bolts 5, and a set of clamps 6, preferably four to a plate, are provided, for engagement by the bolts and these

clamps are each formed with one extremity set out of the plane of the body thereof, so that this bent end will engage the flange of the beam.

It is of course evident that the only requirement in the rail member 8 will be a series of perforations, so arranged as to number and distance apart as may suit circumstances.

With the construction, the end trucks may be applied to rails of any length, being adjusted thereto when the structure is erected, or to be applied afterward, this in contradistinction to the method or practice of building the structure to certain definite distances between the end trucks and then shipping and erecting it as made.

The invention is extremely simple, but the advantages accruing from this form of erecting monorail systems is very evident to all versed in the art.

Having thus fully described my invention, what I claim and desire to secure by Letters Patent is:—

In an adjustable end truck for overhead carriers, the combination of a truck member, a plate on which it is mounted, said plate having a series of bolt receiving perforations, an I-beam on which the truck is adapted to travel, and a set of clamping plates secured and carried by the plate and having bent extremities adapted to engage the flange of the I-beam and to hold the truck end in adjustable position thereon.

In testimony whereof I affix my signature.

RUSSELL E. NELLES.
